UNITED STATES PATENT OFFICE.

RICHARD H. TYNER, OF CINCINNATI, OHIO, ASSIGNOR TO THE NATIONAL MARKING MACHINE COMPANY, OF CINCINNATI, OHIO.

LAUNDRY-SORTING BOOTH.

1,321,953.

Specification of Letters Patent.

Patented Nov. 18, 1919.

Application filed April 3, 1919. Serial No. 287,362.

To all whom it may concern:

Be it known that I, RICHARD H. TYNER, a citizen of the United States, and resident of Cincinnati, in the county of Hamilton and State of Ohio, have invented a certain new and useful Laundry-Sorting Booth, of which the following is a specification.

The object of my invention is to provide a laundry sorting booth of simple, durable 10 and inexpensive construction.

A further object of my invention is to provide a detachable auxiliary sorting and enumerating means for use with a laundry sorting booth of ordinary construction 15 whereby bundles having more articles therein than are provided for in such booths may be conveniently sorted and enumerated.

With these and other objects in view, my invention consists in the construction, arrangement and combination of the various 20 parts of my device whereby the objects contemplated are attained, as hereinafter more fully set forth, pointed out in my claims and illustrated in the accompanying drawings, 25 in which:

Figure 1 shows a perspective view of a laundry sorting booth having my invention installed thereon.

Fig. 2 shows an enlarged detail view of 30 the supporting means of the auxiliary sorting and enumerating means and the parts immediately adjacent thereto.

Fig. 3 shows a vertical, sectional view taken on the line 3—3 of Fig. 2.

Fig. 4 shows an enlarged detail view of 35 the brackets whereby my auxiliary sorting and enumerating device is secured to the laundry sorting booth, and

Figs. 5 and 6 show enlarged details of 40 the sorting and enumerating bars used in connection with a laundry booth.

In the accompanying drawing I have used the reference numeral 10 to indicate generally four vertical spaced supporting rods, 45 which form the corners of my improved booth and which are preferably constructed of iron pipes.

Extended between the various pipes or uprights 10 are horizontal pipes 11, 12 and 50 13 whereby a three sided booth frame is provided. A bracing pipe or rod 14 extends between the tops of the uprights 10 at the fourth side in order to make the structure more solid.

55 Wire screening or wire netting 15 is ex-

tended around the three sides of the booth between the pipes 11 and 12 and between the pipes 11 and the floor. Upwardly inclined shelves 16 formed from similar screening or netting are pivoted at their outer edges to 60 the uprights 10 adjacent to the floor and extended around the three closed sides of the booths. These shelves may be supported by rods 17 or any other suitable means and their purpose will hereinafter be 65 made clear.

Extended between the bars 11 and 12 are a plurality of sorting and enumerating bars 18, which have article receiving hooks 70 consecutively numbered and extending inwardly therefrom. Between the bars 12 and 13 and opposite each of the sorting and enumerating bars 18 is a blackboard 19 adapted to receive the mark or name of the customer.

The sorting and enumerating bars here spoken of consist of channel members, which have the bottom of a channel adjacent to the screening 15 and the sides of the channel extended outwardly therefrom. The 80 hooks mounted in these channel shaped members are designated generally by the reference numeral 20 and comprise an upper loop 21 which has its rear ends pivoted in the sides of the channel and the lower loop 85 22 which has its ends pivoted in the channel in position spaced below the ends of the loop 21. The outer ends of the loops 21 and 22 are formed with right angled extensions 23 and 24 and the loop 22 is provided 90 with an integral ring or collar 25, which slidingly receives the intermediate portion of the hook member 21. Each hook has a number 41 impressed or otherwise placed on the bar 18 adjacent thereto. When sorting 95 and enumerating bars are hereafter spoken of it will be understood that I mean thereby bars of the type just described for laundry receiving hooks thereon which are consecutively numbered.

A U-shaped bracket member 26 is provided with bifurcated ends 27, which may be secured by set screws 28 to the respective pipes 12 and 13. Brackets 26 extend inwardly from the pipes 12 and 13 and support in spaced parallel position relative thereto a second pair of pipes 29 and 30, which extend around the inside of the booth on three sides.

105 Referring to Fig. 4 it will be seen that 110

the bottom or cross portion of the bracket 26 is provided with collars 31, which have openings therein to receive the pipes 29 and 30. The lower arm 32 of the bracket 26 is 5 inclined upwardly and inwardly from the pipes 12 in order that the pipe 30 may interfere as little as possible with the sorter's view of the blackboard 19.

Opposite each of the bars 18 a pair of 10 collars 33 are secured to both pipes 29 and 30 by means of set screws or the like 34. Each of the pairs of collars 33 are spaced from the other member of the same pair and the space between the collars of each pair is 15 directly in front of the adjacent bar 18.

A plurality of auxiliary sorting and enumerating bars 35, which are similar in length and in the arrangement of the hooks 20 to the bars 18, are provided with strips 20 of rigid material 36, which are extended upwardly therefrom. The strips 36 are bent upon themselves at 37 to form a hook 38. The hook 38 is designed to be of such shape and size that it may be tightly received 25 therein above the rods 29 and 30 and in turn be closely gripped between the pair of collars 33 on each of said rods. The bars 35 have impressed or otherwise marked thereon consecutive numbers for each of the 30 hooks 20, which start with the first number above the highest number on the bars 18. These numbers are illustrated on Figs. 5 and 6 where the bars are shown as provided with thirty hooks consecutively numbered 35 and the bars 35 are shown with a similar hook consecutively numbered from 31 to 60.

One of the pipes 12 adjacent to the open side of the booth carries a pair of outwardly extending brackets 39 upon which a horizontal pipe or bar 40 is secured. The pipe 40 is designed to have the auxiliary bars 35 hooked thereover, which are not in use and yet to be so placed that the sorter may conveniently reach this auxiliary bar by stepping to the open side of the booth.

In the practical operation of my improved sorting and enumerating booth all the washed articles mixed indiscriminately together from a given number of bundles are 50 brought to the booth to be sorted out and rearranged into bundles. The lists of articles in these bundles together with the customer's marks are also given to the sorter. The sorter then marks on the blackboard 19 55 each customer's mark or name as shown on the list which he has and then places each article in the pile of washed goods on the lowest unused hook on the bar 18 below the blackboard 19 having the proper mark or 60 name thereon. For example the sorter picks up an article from the pile inspects the mark thereon and then places it on the bar 18 above which appears on the blackboard a similar mark. The articles are always 65 hooked on the lowest unused hook of each

bar, so that as the hooks on each bar become filled up the operator may determine by a glance at the number above the last used hook how many articles have been suspended from the bar by the hooks. The sorter may 70 determine by comparing the total number of articles upon a given bar 18 with the total number of articles enumerated on the customer's list whether it will be necessary for him to check the bundle over to see if all 75 the pieces are there because if the total number on the bar 18 equal the total number in the list he may be very certain that all of the articles belonging to the customer are on the bar.

It will be understood that the shelves 16 are designed to receive the bottoms of the longer articles, which have been washed, to keep the bottoms of said articles off the floor when the articles are hung upon the hooks 20. 85 The operation of the hooks 20 is understood by most laundry sorters but it may be well to here describe the same. A hook 20 when not in use is folded up to substantially vertical position against the bar 18. Referring 90 to Fig. 3 it will be seen that the pivotal point of the loops 21 and 22 are spaced apart so that when the entire hook is swung to substantially vertical position the right angled extensions 23 and 24 will also be spaced 95 apart. If, however, the loops 21 and 22 are then swung to substantially horizontal position the extensions 23 and 24 will approach each other and reach the position shown in Fig. 3. If a laundried article is placed between the extensions 23 and 24 when the loops 21 and 22 are in vertical position and then the loops are swung to horizontal position it will be seen that the article will be gripped between the extensions and the operation is such that a heavy article will pull down more on the loops 21 and 22 thereby thrusting the extensions 23 and 24 more closely into engagement and automatically gripping the article therebetween with the 100 proper amount of pressure to keep it from falling.

The use of the blackboard 19 and the bar 18 has been known for some time and it has been found that only about thirty hooks may 115 be placed on the bar 18 in convenient reach of the sorter, so that where a bundle exceeds that number of articles a large amount of inconvenience results to the sorter in sorting and enumerating the articles exceeding the 120 number of hooks on the bars 18. It may be mentioned, however, that thirty will accommodate a very large per cent. of the laundry bundles, so that it would not be advisable to provide an extra bar 18 at the side of the 125 first bar 18 for each customer because the additional wall space required would entail so many more steps on the part of the sorter that no economy would be secured. The bars 18 cannot have any appreciable increase 130

in the number of hooks because additional hooks either above or below those now provided would be out of convenient reach of the sorter.

5 By means of my auxiliary bars 35 I provide means whereby the bundles which exceed in number of articles, the average maximum number, may be sorted and enumerated in the same manner in which the ordinary 10 bundles are sorted and enumerated and which does not appreciably affect the arrangement of the sorting booth for the convenience of the sorter in sorting the ordinary bundles. If the sorter finds that he has 15 more than the thirty articles, which may be accommodated by a given bar 18, he walks to the front of the booth and reaches for an auxiliary bar 35 from the rod 40 and hooks this auxiliary bar 35 over the rods 29 and 30 20 in front of the filled bar 18. As the bars 35 are consecutive having the hooks thereon numbered consecutively starting with the first number above the highest number on the bars 18, it will be seen that a glance 25 at the number above the last used hook on the bars 35 will instantly disclose the total number of articles, which have been hung on the bar 35 and the bar 18 back of it, so that the sorter may readily compare the number 30 of articles in a bundle having more than thirty articles with the number of articles shown by the customer's list.

Some changes may be made in the arrangement and construction of the various 35 parts of my improved laundry sorting booth without departing from the essential features and purposes of my invention, and it is

my intention to cover by my claims any modified forms of structure or use of mechanical equivalents which may come within 40 their reasonable scope.

I claim as my invention:

1. In a laundry booth, the combination of a series of permanent sorting and enumerating bars provided with means for supporting laundry articles and with consecutively arranged numbers for said means, and a number of auxiliary sorting and enumerating bars similarly provided with means for supporting laundry articles and with numbers for said means arranged consecutively with the numbers on the permanent bars, and means for removably and replaceably supporting said auxiliary bars in fixed position directly in front of any of the permanent bars. 45 50 55

2. In a laundry booth, the combination of a series of permanent sorting and enumerating bars provided with means for supporting laundry articles and with consecutively arranged numbers for said means and a number of auxiliary sorting and enumerating bars similarly provided with means for supporting laundry articles and with numbers for said means arranged consecutively 60 65 with the numbers on the permanent bars, means for removably and replaceably supporting said auxiliary bars in fixed position directly in front of any of the permanent bars, and means for carrying a laundry 70 mark disposed adjacent to each of said permanent bars.

Des Moines, Iowa, November 19, 1917.

RICHARD H. TYNER.
